[57] CLAIM

The ornamental design for the electronic card reader, as shown and described.

DESCRIPTION

FIG. 1 is a perspective view of an electronic card reader showing our new design;
FIG. 2 is a left side elevational view thereof;
FIG. 3 is a right side elevational view thereof;
FIG. 4 is a top plan view thereof;
FIG. 5 is a front elevational view thereof;
FIG. 6 is a bottom plan view thereof;
FIG. 7 is a rear elevational view thereof; and,
FIG. 8 is an enlarged perspective view of an alternative embodiment thereof wherein the only difference is in the omission of a slot along the bottom front panel.
